CLAIM

The ornamental design for a display panel portion with an animated graphical user interface, substantially as shown and described.

DESCRIPTION

FIG. 1 is a front view of a display panel portion with an animated graphical user interface, showing a first image in a sequence;

FIG. 2 is a second image thereof;

FIG. 3 is a third image thereof; and,

FIG. 4 is a fourth image thereof.

The appearance of the animated graphical user interface sequentially transitions between the images shown in FIGS. 1-4. The process or the period in which one image transitions

to another image forms no part of the claimed design. The broken lines showing a portion of a display panel and portions of the animated graphical user interface in FIGS. 1-4 form no part of the claimed design.

1 Claim, 4 Drawing Sheets
